UNITED STATES PATENT OFFICE.

NORA I. SCOTT AND NATHAN G. HANES, OF ATASCADERO, CALIFORNIA.

LINGERIE-STRAP FASTENER.

Application filed March 2, 1925. Serial No. 12,729.

To all whom it may concern:

Be it known that we, NORA I. SCOTT and NATHAN G. HANES, citizens of the United States, residing at Atascadero, in the county of San Luis Obispo and State of California, have invented a new and useful Lingerie-Strap Fastener, of which the following is a specification.

This invention relates to garment supporting shoulder straps and more particularly to fasteners for securing the straps to the garment.

Ladies' undergarments such as camisoles, teddies, shirts and brassières are generally held by individual straps or ribbons which are objectionable because of presenting an unsightly appearance when seen through thin waists such as are now worn.

The object of this invention is to provide a single shoulder strap equipped with means to cooperate with other means on the garments so that at least three garments may be supported by a single strap and if desired more, the straps being detachable for the purpose of laundrying or changing to provide different colors.

Another object of the invention is to provide an elongated pin or bar having a plurality of fastening elements to cooperate with corresponding elements on the garment.

Another object of the invention is to so construct a strap fastener of this character that one strap may be easily changed from one garment to another and the fastener changed from one strap to another so that clean fresh straps may be provided at all times and at a moment's notice.

A further object is to provide a strap fastener of this character which is smooth and will not injure the flesh or the clothing and yet is strong and durable.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—
Figure 1 represents a front elevation of a plurality of garments with this improved

strap fastener shown applied, the strap being twisted at its lower end to show the opposite side of the fastener;

Fig. 2 is a section taken on the line 2—2 of Fig. 1;

Fig. 3 is an enlarged front elevation of the fastener shown in Fig. 1 detached;

Fig. 4 is a transverse section taken on the line 4—4 of Fig. 3;

Fig. 5 is a front elevation showing a slightly different form of fastener; and

Fig. 6 is a transverse section taken on the line 6—6 of Fig. 5.

In the embodiment illustrated in Figs. 1 to 4 inclusive a shoulder strap 1 is provided which may be composed of any desired material and which is equipped at its opposite ends with a safety pin 5 composed of resilient wire bent to form parallel rods 6 and 7 without any coils at their junction such as is usually found in safety pins. The rod 6 is provided at its free end with a laterally extending hook 8 which is designed to receive the pointed terminal 9 of rod 7 which projects beyond the hook 8 and detachably connects the two rods, it being designed to secure these members after the pointed rod 7 has been threaded through the end of the strap 1 or inserted in a casing 2 formed at the end of said strap.

Hingedly carried by the rod 6 is an elongated plate or bar 10 equipped along one side edge with spaced hooks or eyes 11 any desired number of which may be employed two being preferably used and located adjacent the ends of the plate 10. These hooks 11 are engaged with the rod 6 to form the hinged connection between the plate 10 and said rod.

The plate 10 is provided on its opposite edge with a plurality of hooks 12 spaced suitable distances apart, three of which are here shown and which extend in a direction opposite to the hooks 11 carried by the other edge of the plate. These hooks 12 preferably have their terminals flared outwardly to facilitate their engagement with eyes 13 carried by the respective garments to be supported.

As shown three garments numbered *a*, *b* and *c* are arranged in superposed relation, *a* being the innermost with a reinforcing tab 14 fixed adjacent the upper edge thereof and which carries the loop or eye 13 to be engaged by one of the hooks 12 of the fastener. It is of course understood that these tabs 14

are preferably arranged on the inner faces of the garments so as to be invisible and are disposed below the trimming which ordinarily forms a part of said garments.

5 It will thus be seen that a strap 1 equipped with these improved fasteners may be readily connected with or disconnected from the garments to be supported by simply engaging the hooks 12 with the eyes 13 or removing them from such eyes as the case may require. The fasteners are also readily removable from this strap by disengaging the pointed rod or pin 7 from the strap permitting the straps to be laundered or changed 10 15 as desired.

In the form shown in Figs. 5 and 6 the strap carrying fastener member is constructed of wire entirely made from a single piece and bent to provide a strap engaging rod 20 7^a which is interengaged with a hook 8^a formed at the other end of the wire.

The wire from which the fastener shown in Figs. 5 and 6 is constructed is bent to provide the hooks 12^a, three of which are shown 25 and which are connected by curved portions 15.

The rod 7^a is preferably made blunt at its free end in this form of the fastener to permit it to be readily inserted through the 30 casing 2 of the strap and to avoid danger of the pricking of the flesh of the wearer.

While metal eyes 13 are shown connected with the garment to be supported obviously any form of loops may be used for this purpose.

We claim:

1. The combination with a plurality of individual garments each having a fastener, said fasteners being arranged in longitudinal alignment when in use; and an elongated 40 bar having attached means for connection with a strap and provided with a plurality of longitudinally spaced fastening elements to cooperate with the individual elements on the garments whereby a plurality of garments may be suspended from a single strap. 45

2. A fastener of the class described comprising a plate having longitudinally spaced hooks along its opposite side edges, those on one side extending in a direction opposite to those on the other, an attaching member connected with the hooks at one side edge of said plate, the hooks at the other side edge being designed for engagement with loops 50 55 on the garment to be supported.

In testimony that we claim the foregoing as our own, we have hereto affixed our signatures.

NORA I. SCOTT.

NATHAN G. HANES.
